UNITED STATES PATENT OFFICE.

JOHN WHITAKER, OF NORTH WALES, PENNSYLVANIA.

MACHINE FOR PRINTING AND SCARRING PAPER.

1,213,049.

Specification of Letters Patent.

Patented Jan. 16, 1917.

Application filed October 4, 1916. Serial No. 123,679.

To all whom it may concern:

Be it known that I, JOHN WHITAKER, a citizen of the United States, and a resident of North Wales, county of Montgomery, 5 State of Pennsylvania, have invented certain Improvements in Machines for Printing and Scarring Paper, of which the following is a specification.

My invention relates to certain improvements in means for scarring paper, said means being particularly applicable to apparatus for printing amounts on checks, drafts, &c., with ink and tearing the surface of the impressions so as to make it very difficult to alter the printed amount.

One object of my invention is to provide a machine which will make type impressions in connection with a movable platen, which moves when an impression is made so as to 10 tear or separate the fibers of the paper.

A further object of the invention is to provide a printing and scarring machine in which plain faced type is used and in which the scarring or tearing of the paper is 15 accomplished solely by the platen.

A still further object of the invention is to provide means for piercing and then slightly separating or opening up the fibers of the paper from one side while pressure 20 is being applied to the opposite side of the sheet.

My invention also relates to a peculiar construction of platen fully described hereinafter.

35 In the accompanying drawings:—Figure 1, is a transverse sectional view of my improved printing machine illustrating my invention; Fig. 2, is a front view, showing the base in section, on the line 2—2, Fig. 1, and 40 a portion of the overhanging frame in section; Fig. 3, is a perspective view of one of the elements of the platen; Fig. 4, is a detached perspective view of a portion of the platen; Fig. 5, is a detached perspective 45 view of part of the carrier in which the platen is mounted; Figs. 6, 7 and 8, are diagram views showing the relation of the platen to the type wheel; Fig. 9, is a detached perspective view of a modification of the platen; Fig. 10, is a sectional view illustrating another modification; Fig. 10^a, is an 50 enlarged sectional view of a portion of Fig. 10; Fig. 11, is a perspective view of one of the elements illustrated in Fig. 10; Figs. 55 12 and 13, are views illustrating further modifications of the invention; Fig. 14, is a

sectional view of a check writing machine provided with my improved platen; Fig. 15, is a sectional view of a machine in which the platen elements are moved by mechanism independent of the type carrier or cylinder; Fig. 16, is a sectional view in which the platen is made of alternate sections, one set being stationary and the other set laterally movable; Fig. 16^a, is a detached perspective view of the parts of the platen shown in Fig. 16; Fig. 17, is a view of a modification of the platen illustrated in Fig. 4, and Fig. 18, is a detached perspective view of the platen operating mechanism 60 shown in Fig. 15.

65 Referring to Figs. 1 and 2 of the drawings, 1 is the base of the machine supporting an overhanging frame 2, which is spaced from the base to form a passage 3 for the check, or other paper, to be scarred and printed. 4 is the type cylinder having a series of independent type faces 5, in the present instance extending parallel with the axis of the type cylinder. Each of these 70 faces has different characters thereon, in the present instance reading from "Not over two dollars" to "Not over five hundred dollars" inclusive, and, on turning the wheel, any one of these phrases can be brought into 75 alignment with the platen. The faces of the type in this instance are smooth and are hardened so as to withstand the piercing and action of the platen hereafter described. 80 The type cylinder may be formed in many 85 different ways, but it should have a comparatively hard impression surface, and I preferably make the shell of the cylinder of steel. The type or impression surface is preferably formed by etching upon the surface of the steel sheet while flat, the sheet being then bent into shape and secured to the body portion, but the etching may be done after the shell has been secured to the body portion, or the type may be stamped 90 up from the steel sheet, or the cylinder may be cast in type metal and the surface plated with nickel or other suitable material. The shaft 6 on which the cylinder is mounted is carried by eccentric bearings 7 adapted 95 to the frame 2. The handle 8 is secured to these eccentric bearings so that on turning the handle the cylinder is moved toward the platen in order that the type may make an 100 impression. A spring 9 returns the handle 105 and cylinder to normal position, as illustrated in Fig. 1. On the shaft 6, to which the

cylinder 4 is secured, is a hand wheel 40 having characters corresponding with the characters on the cylinder, and 41 is a pointer loosely mounted on the shaft 6 so as to travel with the shaft and the parts secured thereto when the handle 8 moves the cylinder toward the platen. 42 is a pawl which engages the notches 43 in the cylinder 4 so as to hold the cylinder in the position to which it is adjusted. 10 is an inking roller carried by a spring frame 11, and inks the several lines of type as they pass it when the cylinder is rotated. 12 is a re-inking brush carried by a frame 13, and moves across the face of the type as the cylinder is moved toward the platen and re-inks the type without the necessity of turning the cylinder so that the type will pass the inking roller; the brush also acts to clean the type from any excess of ink, insuring a perfect impression. This mechanism is fully described in an application for patent filed by me on the 16th day of October 1915, under Serial No. 56,307. Mounted on the base 1 is a carrying plate 14 for the platen 15. This carrying plate is secured at the rear to a lug 16 on the base 1 by screws 17 and at the forward end are adjusting screws 18, which bear upon a flange 19 on the base so that, by turning the screws, the platen can be adjusted in respect to the cylinder 4; the forward end of the carrying plate being guided by pins 20, which extend into openings in the frame 1. The carrying plate 14 is recessed at 21 to receive the platen 15, which consists of a series of thin elements 22, preferably loosely connected at their base by a pin 23 and assembled, as shown in Figs. 2 and 4. They are held in place in the recess 21 by blocks 24 secured to the plate 14 by screws 25, Fig. 2. Each element of the platen consists of two arms 26 and 27. The arm 27 is shorter than the arm 26 and this latter arm has an overhanging portion 28 serrated at 29, or otherwise formed to provide a piercing and tearing or cutting member which preferably passes entirely through the paper. The arm 26 is beveled at 30 and the arm 27 is beveled at 31, and these beveled surfaces rest against the edges 32 of the recess 21. By loosely mounting the elements on the pin 23 they can be readily assembled and the serrated surfaces of the elements will be brought to the same level when pressure is applied as the beveled surfaces 30, 31 of the elements come in contact with the edges 32 of the recess in which the platen is mounted, insuring an even penetration of the paper throughout the length of the platen. Upon referring to the drawings, it will be noticed that the elements are so arranged that the arms 26 of one set of elements are on one side and the arms 26 of the alternate elements are on the opposite side, so that, when pressure is applied, one set of

elements moves in one direction, while the other set of elements moves in the opposite direction. By this construction the serrated faces of the several elements will pierce and open the fibers of the paper when an impression is being made by the type cylinder. Figs. 6, 7 and 8 of the drawings fully illustrate this construction. The projecting points, forming the serrated face of each element, pierce the paper when an impression is made and, as they move laterally, they tear or open up the fibers, making it practically impossible to erase the printed matter, yet the printed matter is not disfigured to any appreciable extent, as the points enter from the opposite side of the sheet.

In Fig. 9, I have shown a modification of the platen, in which the tearing or cutting face, instead of being composed of teeth, consists of a series of knife edges 29^a and these edges are alternately beveled so that, as they penetrate the paper, the lateral movement will cause a separation or tearing of the paper in addition to cutting.

In Figs. 10, 10^a and 11, I have illustrated a modification in which the platen consists of a series of longitudinally arranged elements 22^a located side by side and the serrated face section 28^a of each element is continuous, and extending from each section is a series of diagonal or curved arms 26^a. The arms of the several elements are secured together by rivets 23^a, or other fastenings. The arms are preferably reduced at the point where they connect with the face section, so that they will yield to the pressure of the type form. The action is similar to the construction illustrated in Figs. 1 and 2, i. e., when the cylinder is making an impression the alternate elements will move in opposite directions and will serrate or tear the paper.

In Fig. 12, I have shown another modification of the platen. In this instance, the elements 26^b and 27^b are pivotally connected and their outer ends rest upon shoulders on the carrying plate 14^b, while the projecting portions rest upon a pad 33 of rubber, or other suitable flexible material. The upper edges of these sections are serrated. When pressure is applied to the platen, the rubber cushion is compressed and the alternate sections are moved laterally at the serrated edge.

In Fig. 13, I have illustrated a modification in which the cushion is dispensed with and the sections 26^c and 27^c have spring tongues 26^d and 27^d, respectively. These tongues rest on the shoulders formed on the carrying plate 14^c, as clearly shown in the drawings, so that, when pressure is applied, the alternate sections will have a lateral movement.

In Fig. 14, I have illustrated my im-

proved platen applied to a check writing machine, such as that illustrated in the application for patent filed by me on the 20th day of November 1915, Serial No. 62,535, and in this machine some of the elements of the platen may act in conjunction with the type of a type carrier, while other portions may act with a plain surface to tear the fiber of the paper when the check is written upon by hand. The detailed construction of the platen is similar to that illustrated in Figs. 1, 2, 4 and 5.

In Figs. 15 and 18, I have illustrated a machine in which the movement of the elements of the platen is controlled by mechanism independent of the type cylinder. 35 is a lever actuated by a shaft 6 on which the type cylinder 4 is mounted, the lever is secured to the rock shaft 36 adapted to bearings in the frame and is connected by links 37 and 38 to the elements of the platen 15. These elements are assembled in the same manner as the elements of Figs. 1 and 2. In the present instance the alternate elements are connected together by rods 37^a while the other elements are connected by rods 38^a, and the links are coupled to these rods. There is a duplicate set of links at the opposite side of the machine, as shown in Fig. 18 and there may be a duplicate lever 35, if desired. When the shaft 6 is turned it will come in contact with the end of the lever 35 as the cylinder is making the impression, causing the alternate elements of the platen to move in one direction and the others to move in the opposite direction, so as to open up or separate the fibers of the paper simultaneously with the impression.

40 Figs. 16 and 16^a illustrate a modification in which some of the elements 22^b are stationary as regards lateral movement so as to hold the paper while the other elements move laterally to tear it.

45 In Fig. 17, I have shown a modification of the platen, in which the beveled surfaces are on the inner sides of the elements of the platen 15^a, and which rest against a central bar 32^a. Springs hold the elements against 50 the bar.

It will be understood that while my invention is particularly adapted to a machine which prints and scars the paper, it can be used simply for the purpose of scarring and 55 opening the fibers of the paper where the amount of other matter has been written on the paper by hand, or by a type writer.

Referring to Figs. 1, 2, 6, 7 and 8, the operation of the apparatus is as follows:—If 60 it be desired to print a given amount on a check, for instance, then the cylinder is turned by its hand-wheel so that the proper type face will be in alignment with the platen. The check is then inserted in the 65 space 3, suitable stops being employed to

hold the check in proper position. The handle is then turned so as to cause the cylinder to move toward the platen, the type face having been previously inked by the mechanism above described. As the type 70 face makes the impression it also presses upon the platen, causing its sections to move downward, and the pressure of the inclined portions of these sections against the upper edges 32 of slot 21 causing the two arms 26 75 and 27 of each section to move toward each other. This movement causes the serrated surfaces of each section to move laterally, and, as the sections are alternately arranged as hereinbefore described, one section will move to the left and the other to the right, piercing and tearing or scarring the paper so that the ink on the type cylinder will penetrate the scarred paper, making it extremely difficult for any one to obliterate the 80 impression after it has been made. As soon as the impression is made, the spring will return the handle and the cylinder to the normal position and the elements of the platen will also return to their normal positions, due to the spring construction of the 85 several elements. By causing the type cylinder to roll toward the platen the cylinder contacts first with one edge thereof and rolls over the balance of the projections, progressively making the incisions in the paper, so that comparatively little pressure is required in operating the machine.

Fig. 6 illustrates the platen in position prior to the movement of the type cylinder 100 to make the impression; Fig. 7 illustrates the first contact at one edge of the platen, and Fig. 8 illustrates the position of the elements of the platen when an impression is made.

I claim:—

1. In an apparatus for scarring checks and other papers, a platen having fiber piercing elements; means for pressing the check against the platen to thereby cause said elements to pierce the paper; and means 110 co-acting with the first named means for moving platen elements laterally substantially simultaneously with the piercing of the paper to thereby open the fibers of the pierced paper and thus scar the check.

2. In an apparatus for scarring checks and other papers a movable platen consisting of a series of elements each element having a scarring surface; a support therefor; and means for pressing the check against the platen so that the surface of the latter will penetrate the paper, said support including means for causing the elements of the platen to move laterally substantially simultaneously with the penetration of the paper to 125 thereby separate the fibers of the paper and thus scar the check.

3. In an apparatus for printing and scarring paper, the combination of a type form for making an impression; a platen having 130

fiber piercing elements; and means co-acting with the type form for displacing platen elements laterally to cause them to open up the fibers of the penetrated paper substantially simultaneously with the making of the impression.

4. In an apparatus for printing and scarring paper, the combination of a type form; means for inking the form; and a yielding platen having laterally moving piercing elements constructed to pierce the paper and substantially simultaneously open the fibers thereof as the impression is being made.

5. The combination in apparatus for printing and scarring paper, of a type form having smooth faced type thereon; means for inking the type; a sectional platen; means for moving one element of the printing couple toward the other to cause an impression to be made on the paper between the elements, each section of the platen having a piercing device to pierce the paper; and means to cause sections of the platen to move laterally to open up the fibers of the paper as an impression is being made.

6. The combination in a device for printing and scarring paper, of a type form having smooth faced type thereon; means for inking the type; a platen; and means for causing the type to make an impression on the paper located on the platen, said platen consisting of a series of alternately arranged thin plates, each plate having a serrated edge; a carrier for the platen so formed that said platen will yield under pressure; and means for causing the plates to move laterally as the platen yields, some of said plates moving in one direction and others moving in the opposite direction so that the paper is pierced and the fibers opened simultaneously with the printing.

7. In an apparatus adapted for printing on checks, the combination of a printing cylinder having type lines formed thereon; means for turning the cylinder; a platen consisting of yielding sections having serrated faces adapted to pierce the paper; and means for causing the sections of the platen to move laterally so that substantially simultaneously with the making of the impression the platen sections will pierce the paper and open the fibers.

8. The combination in an apparatus adapted for printing on checks, of a frame having a base; a platen carried by said base, said platen consisting of a series of narrow sections having piercing edges; means for yieldingly supporting the sections so that when pressure is applied they will move laterally; a printing device carrying type and arranged to make an impression on paper located between the device and the platen; and means for causing an impression to be made simultaneously with the piercing of the paper by the sections of the

platen which also move laterally to open the fibers of the paper.

9. The combination in a printing device for printing amounts on checks, of a frame; a base; a platen mounted in the base consisting of a series of thin spring plates placed side by side and having penetrating surfaces, the alternate plates being arranged to move in a direction opposite to the other plates; and means carried by the frame for making an impression on a paper located on the face of the platen, said base having means for causing the plates to move laterally to separate the fibers of the paper substantially simultaneously with the penetration of said paper by the platen.

10. The combination in apparatus for printing amounts on checks, of a frame; a base having a recess therein; a platen consisting of independent spring plates having inclined portions resting on the edges of the walls of the recess, each spring plate having two arms, one arm carrying a serrated surface forming the face of the platen; said arms being so arranged that, when pressure is applied, alternate arms will move laterally in one direction, and the other arms will move laterally in the opposite direction and means carried by the frame for making an impression on a sheet of paper on the platen, so that the paper will be scarred at the same time that an impression is made.

11. The combination in apparatus for printing amounts on checks, of a frame; a base; a platen mounted in the base and formed of a series of independent spring plates each having a roughened upper surface adapted to pierce the paper; a type cylinder having a plurality of type lines; means for turning the type cylinder to move any of the type lines into alignment with the platen; and means for making an impression by the type on a sheet of paper located on the platen, said base having means for causing the plates to move laterally to separate the fibers of the paper at the same time that an impression is made.

12. The combination in apparatus for scarring checks and other papers, of a platen-carrying frame; a movable platen made up of a series of piercing elements mounted side by side and means for pressing the paper against the platen to thereby pierce the paper, each element of the platen having inclined portions adapted to a recess in said carrying frame whereby the elements are caused to move laterally substantially simultaneously with the piercing of the paper.

13. The combination in an apparatus for printing and scarring paper, of means for making an ink impression on one side of the paper; and a platen having laterally movable elements, each of said elements having

a roughened face constructed to penetrate the paper from the other side and open up the fibers of the paper substantially simultaneously with the making of the ink impression, so as to make it difficult to alter the printing on the face of the paper.

14. The combination in a protector for checks and like papers, of a platen made up of elements capable of moving to a limited extent in opposite directions when pressure is applied to the platen, and having serrated surfaces for piercing the paper and substantially simultaneously therewith opening up the fibers of the paper without materially disturbing the printed or written matter on the surface of the paper.

15. The combination in a protector for checks and like papers, of a platen made up

of piercing elements; means for causing the elements to move laterally, as an impression is made; an impression device co-acting with the platen, said impression device having smooth and hard faced characters so that when an impression is made the piercing elements of the platen will pierce and open up the fibers of the paper without disfiguring the impression.

16. The combination of a platen having a series of piercing elements; an impression device for pressing the paper into the platen, and means for imparting to elements of the platen a limited lateral movement so as to open the fibers of the paper without destroying the surface thereof.

JOHN WHITAKER.
